CENTRIFUGAL APPARATUS

Eugene Roberts, Hastings, N. Y., assignor to The
Western States Machine Company, New York,
N. Y., a corporation of Utah

Application July 22, 1935, Serial No. 32,539

3 Claims. (Cl. 210—67)

This invention relates to centrifugal apparatus of the type commonly used for separating the mother liquor from the solid particles contained therein, a type which is commonly used in sugar factories or chemical plants in which it is the practice to suspend a perforated centrifugal basket to revolve inside an enclosing curb or casing, the top of the casing and the top of the basket being open to facilitate access to the interior of the basket for the purpose of loading the centrifugal, observing it while in operation and unloading the contents after centrifuging is completed.

In such centrifugals there is a strong uprush of air through the open top of the curb, which air is both hot and moist due to the vapor or fumes produced by the continual supply of warm wet material to the basket. This expulsion of hot damp air renders attendance upon the centrifugals unpleasant and sometimes deleterious to the operators, beside creating more or less disturbance to the finely divided spray which is used to wash the walled up material in the basket after the purging has been completed.

The object of the present invention is to eliminate these objectionable features and to provide a very simple and inexpensive construction and arrangement which is effective for the purpose. In general, the invention comprises an arrangement of a centrifugal basket inside a surrounding casing which is provided, at a convenient location on one side, with a discharge opening leading to an exhaust pipe through which the air and vapor laden air inside the curb are exhausted and carried away, while at the same time counteracting or preventing the uprush of air through the open top of the casing.

In the accompanying drawing is illustrated a simple and convenient arrangement embodying the principles of this invention, in which

Fig. 1 is a side elevation of a suspended centrifugal with its surrounding curb to which is connected intermediate of its top and bottom an exhaust pipe for serving the intended purposes.

Fig. 2 is a front elevation showing part of a battery of centrifugal machines, each exhaust pipe leading to a manifold exhaust with which is connected an exhaust fan for maintaining the desired circulation.

Fig. 3 is a horizontal section showing a baffle arrangement at the intake end of the exhaust pipe.

The centrifugal machine itself is of a well known type and comprises a basket carrying shaft 1 to the lower end of which is secured any usual

or well known perforated centrifugal basket 2 having a top partly closed by an annular rim shown at 2a.

Following the usual practice, the basket shaft is suspended from an overhead fixed hanger 6 to permit gyration and is provided with suitable driving means, such as a pulley 7 and a well known type of external brake 8 which serves to slow down and stop the centrifugal at the requisite intervals.

Surrounding the centrifugal basket, but at a sufficient distance to permit the basket to gyrate when coming up to speed, is a cylindrical casing 9 provided with a top ring or rim 10, leaving a large opening for access to the interior of the 15 basket. At any convenient point, preferably in most cases at the rear opposite the point where the operator stands, I provide an outlet opening in the casing between the top and bottom thereof and connect with this outlet opening an exhaust 20 pipe 11 leading to an overhead manifold exhaust 12, which receives the exhaust from all centrifugals of the battery and which leads to an exhaust fan conventionally shown at 15.

A baffle arrangement is preferably provided at the outlet opening in the curb to deflect the centrifugally extracted liquid down to the bottom of the curb instead of expelling a portion of it into the lower end of the exhaust pipe. In the present case the baffle is shown as comprising spaced overlapping plates that are in staggered relation to one another but any convenient construction of baffle that will allow the air to pass freely out of the casing through the exhaust pipe may be used, or the baffle may be entirely omitted in cases 30 where it may be preferred to dispense with it. As shown in Fig. 3, the liquid which is centrifugally expelled through the perforated basket wall 2 is prevented from being carried into the exhaust pipe by means of a baffle inserted at the intake 35 end of the exhaust pipe 11. This baffle in the form shown comprises a convergent or funnel-like intake ring 18, in which are mounted a series of baffle plates which are preferably slightly concaved and extend vertically in two offset series 40 19 and 20 in mutually staggered relation, affording ample opportunity for the air to pass through the exhaust conduit while at the same time so disposed as to catch and direct downward into the bottom of the liquid collecting casing 9 the 45 expelled liquid just as does the remainder of the side wall of the casing. The baffle plates receive the direct impact of the liquid expelled from the basket and guide the liquid downward, while the funnel-shaped portion of the baffle supporting 50

55

annulus facilitates drainage of liquid to the bottom of the casing.

- 5 By creating a suction or partial vacuum in the space between the basket wall and the curb wall it will be seen that the hot moist fumes rising from the interior of the basket are diverted or drawn through the narrow space between the annular open basket top and the annular open casing top, so that the upward flow of such 10 fumes, whether from the basket or from the space surrounding the basket through the open top of the casing, is prevented. This prevents the gumming up of the overhead apparatus beside affording effective protection to the centrifugal operating 15 atom from the hot fumes that heretofore have issued through the open top.

What I claim is:

1. In an apparatus for centrifuging sugar or like material, the combination of a gyratory centrifugal comprising a perforated open top basket suspended by a central driving spindle, a fixed stationary casing surrounding the centrifugal basket in spaced relation permitting requisite gyration of the centrifugal and having an annular 20 open top rim overhanging the top rim of the basket and spaced therefrom to provide an unobstructed passage between said rims, an exhaust 25

conduit connected with the casing between the bottom and the top thereof, and means for drawing fumes arising from the interior of the basket through the annular space between the basket rim and the casing rim through said outlet conduit. 5

2. In a centrifugal apparatus the combination of a perforated centrifugal basket, a surrounding casing open at its top, an exhaust pipe having communication with the interior of the casing, 10 means for exhausting air from the casing through said pipe, and a baffle device arranged at the intake end of the exhaust pipe and permitting the inflow of air from the casing while deflecting the liquid toward the bottom of the receptacle. 15

3. In a centrifugal apparatus the combination with a perforated centrifugal basket, a surrounding casing provided with an open top, an exhaust pipe leading from the side of the casing, means for exhausting the air from said casing through 20 said pipe, a liquid baffle device located at the intake of said pipe and comprising vertical baffle plates in spaced staggered relationship to one another and acting to deflect toward the bottom 25 of the casing the liquid centrifugally expelled from the subtending portion of the basket.
